UNITED STATES PATENT OFFICE.

GERTRUDE L. NICKERSON, OF BRIDGEPORT, CONNECTICUT, ASSIGNOR TO THE WARNER BROTHERS COMPANY, OF BRIDGEPORT, CONNECTICUT, A CORPO-RATION OF CONNECTICUT.

DESIGN FOR A CORSET.

Specification for Design.

Patented July 4, 1922.

Application filed April 5, 1922. Serial No. 1,557. Term of patent 14 years.

To all whom it may concern:

Be it known that I, GERTRUDE L. NICKERSON, a citizen of the United States, residing at Bridgeport, county of Fairfield, and State of Connecticut, have invented a new, original, and ornamental Design for Corsets, of which the following is a specification, reference being had to the accompanying drawing, forming part thereof.

The figure shows a corset embodying my new design, as such a corset appears on a wearer.

The essential feature of my design is the graceful curve of the rear top edge, so arranged that the rear center portion of the top edge is higher than the side portions thereof.

I claim:

The ornamental design for a corset, as shown and described.
